United States Patent Office.

JOHN J. SANDERS, JR., OF NEW YORK, N. Y.

Letters Patent No. 78,330, dated May 26, 1868.

IMPROVEMENT IN MITRING-MACHINES.

The Schedule referred to in these Letters Patent and making part of the same.

TO ALL WHOM IT MAY CONCERN:

Be it known that I, JOHN J. SANDERS, Jr., of New York, in the county and State of New York, have invented a new and improved Mitring-Machine; and I do hereby declare that the following is a full, clear, and exact description thereof, which will enable others skilled in the art to make and use the same, reference being had to the accompanying drawings, forming part of this specification.

Figure 1 represents a side elevation of my improved mitring-machine.

Figure 2 is a plan or top view of the same.

Figure 3 is a vertical transverse section of the same, taken on the plane of the line *xx*, fig. 1.

Figure 4 is a detail face view of my combined saw and planer.

Figure 5 is a detail face view of my improved plane attachment.

Figure 6 is a longitudinal sectional view of the same.

Similar letters of reference indicate corresponding parts.

This invention relates to a new machine for mitring mouldings and other articles, and consists, first, in a new manner of combining planing-knives with circular saws, so that the edges of the mouldings which are being sawed may at the same time, and by the same instrument, be planed.

The invention consists, second, in a new manner of constructing circular-saw blades, with a view to reduce their expense, and to prevent them from shrinking.

The invention consists, third, in a new manner of attaching the planing-irons in their cases, which is done so that the face of each planing-iron remains perfectly smooth, no fastening-screws projecting from the same, nor any slots being arranged through them.

The invention consists, fourth, in the manner of constructing the sliding table of my improved mitring-machine, so that the length of the mouldings to be cut can be gauged at will, whereby much time and labor are saved.

The invention, finally, consists in the general arrangement and combination of the parts which constitute my improved mitring-machine.

A, in the drawing, represents the frame of my improved mitring-machine. The same is made of suitable material, size, and shape, and sufficiently strong to support the shafts and machinery pertaining to my mitring-machine.

B is a horizontal shaft, having its bearings in the frame A, and receiving rotary motion, of any desired velocity, from suitable mechanism. Upon each end of the shaft B, or at least on each side of the frame A, is mounted on the shaft B a circular block, C, made of metal or other suitable material. Each block, C, carries an annular saw-blade, D, and a suitable number of planing-knives, E E.

The saw-blade D is annular, and has a flange, *a*, which projects from one face, as shown. This flange *a* strengthens the blade, and prevents it from shrinkage, and serves to secure the blade to the block C by means of bolts or screws *b b*, as shown more particularly in fig. 3. The teeth are formed either directly on the saw-blades, as shown, or are attached to the same in any suitable manner. The block C is perforated for the reception of the planing-knives E E, as shown. The edges of the knives fit into grooves *c c*, which are provided in the block C, as indicated in fig. 6. The knives are perfectly smooth on their surface, no slots or perforations being cut through the same. The lower face of each knife rests upon a wedge-shaped block, F, which is arranged in the block C, and which can be moved back and forth by means of a screw, *d*, as in fig. 6. The block F, resting upon an inclined surface, is, when moved by the screw, caused to move up or down, as may be desired. When the knife is fitted into the slot in the block C, so that its edges are in the grooves *c*, the screw is turned, so as to force the wedge F against the knife, when the latter will be firmly clamped between the said wedge and the upper edge of the groove. The knife will thus be firmly secured in the block, and will not be able to move spontaneously in the block C.

The knives E are in this manner left with a smooth surface, and shavings can, consequently, not be clogged.

in the apertures of the block C. This part of my invention is also applicable to ordinary carpenters' planes, as the smooth-faced planing-iron is a decided improvement.

The cutting-edges of the knives E project from the inner faces of the blocks C, to which, also, the saw-blades D are attached, as in fig. 3.

Upon the frame A is arranged, between the blocks C, a sliding horizontal carriage, G, which receives reciprocating motion by suitable mechanism. Upon the face of this carriage are fitted one or more projecting V-shaped blocks or guides, H, in the manner shown in fig. 2, which serve as rests for the mouldings to be cut on either side. The carriage is also provided with a sliding gauge, e, which is arranged at or near the edge of one of the blocks H, and which serves to indicate the length of the moulding to be cut, to facilitate which a graduated scale may be marked on the face of the carriage G, as indicated in fig. 2.

When a moulding is to be mitred, its proposed length is first determined by adjusting the gauge e. The moulding is then put with one end against the gauge, and with a side against the block H, and the carriage is moved forward, so that the portion of the moulding which projects from the table G may, by the saw, be severed from that resting on the table. The edge of the latter piece is then planed by the cutters E. By having the gauge e, any desired number of mouldings may be quickly mitred, so as to be of exact equal length.

The machine may be provided with one set of saws and planes, or with two, as shown.

I claim as new, and desire to secure by Letters Patent—

1. The block C, attached to the saw D, for the purpose of holding the planing-knives E, all constructed, arranged, and operating as described, for the purpose specified.
2. The adjustment of the planing-knives E in the block C, by means of the inclined grooves e, nut F, and screw-bolt d, all constructed, arranged, and operating as described, for the purpose specified.

JOHN J. SANDERS, JR.
